UNITED STATES PATENT OFFICE

2,140,665

PAPER CUP MAKING MACHINE

Herman Carew, Easton, Pa., assignor, by mesne assignments, to Dixie-Vortex Company, Chicago, Ill., a corporation of Delaware

Application August 3, 1935, Serial No. 34,606

41 Claims. (Cl. 93—36.05)

My invention relates to new and useful improvements in a machine for making paper receptacles or containers and more particularly to a machine for making paper cups of the type, 5 illustrated in my Patent No. 1,972,006, dated August 28, 1934, having an open self-extended mouth and a downwardly tapered rounded body terminating on a wedge-shaped bottom.

The principal object of the invention resides 10 in the provision of a machine of the character described in which cups are made from suitable blanks of material, each cup being formed from a single piece of material folded on a medial transverse line to provide opposite wall portions, 15 edges of the wall portions being overlapped and secured together.

Another object of the invention consists in the provision of means for supporting a stack or stacks of the blanks from which the cups are 20 to be formed and means for feeding the blanks to the forming mechanism, said forming mechanism folding the blanks into the desired shape.

A further object resides in the provision of male and female die members, the male member 25 engaging the blank to force the same into the female member, the members co-operating to shape the blank to provide a cup or receptacle having a normally open mouth portion and a downwardly tapered rounded body terminating in a wedge-shaped bottom.

Still another object consists in the provision of a substantially wedge-shaped member adapted to engage a blank, the blank being folded around the member into cup formation, and means for 30 securing overlapped edge portions to maintain said formation.

A still further object consists in the provision of a substantially wedge-shaped forming member adapted to engage a blank, and cooperating 40 means for folding the blank, during the movement of the substantially wedge-shaped member into cup formation, means being provided to secure overlapped edge portions of the blank to maintain said formation.

Another object resides in the provision of a 45 wedge-shaped forming member adapted to engage a blank, cooperating means for folding the blank, during movement of the wedge-shaped member, into cup formation, a female member to receive the wedge-shaped member and cup carried thereby to give final shape to the cup, and means for securing the over-lapped edge portions of the cup.

Another object of the invention consists in the 55 provision of means for supporting a stack of

blanks and a member adapted to be operated for removing the uppermost blank from the stack, said removing member including portions adapted to receive an adhesive, the adhesive engaging the blank and supporting the same on the member, means being provided to disengage the blank from the supporting member for deposit onto a carrier which moves the blank into a forming zone.

A further object consists in the provision of a 10 novel form of carrier to receive the blank from the member which removes the same from the stack, and means for positioning the blank on the carrier in proper position to be engaged by formers which fold the blank into cup formation. 15

A still further object of the invention resides in the provision of a member adapted to be engaged with a blank, cooperating means for folding the blank on a medial transverse line to provide opposite wall portions, and means for folding 20 the wall portions around the member and to overlap the edges thereof.

Still another object of the invention resides in the provision of a rotatable member having circumferentially spaced pockets, cooperating means 25 for shaping blanks into cup formation and depositing the same successively into the pockets as the member is rotated, and means for successively removing the formed cups from the pockets.

With the above and other objects in view, which will appear as the description proceeds, my invention consists in the novel details of construction and arrangement of parts described in the following specification and illustrated in the accompanying drawings, and while I have illustrated 35 and described the preferred embodiments of the invention as they now appear to me it will be understood that such changes may be made as will fall within the scope of the appended claims.

In the drawings:—

Fig. 1 is a front elevation of the supporting frame structure.

Fig. 2 is a side elevation of the supporting frame structure.

Fig. 3 is a vertical central section on the line 3—3 of Fig. 1.

Fig. 4 is a rear elevation of the supporting frame structure.

Fig. 5 is a front elevation of the complete machine.

Fig. 6 is a rear elevation of the complete machine.

Fig. 7 is a right hand side elevation of the complete machine as viewed in Fig. 5.

Fig. 8 is a top plan, enlarged, of the complete machine.

Fig. 9 is a horizontal section on the line 9—9 of Fig. 7, looking in the direction of the arrows, 5 with parts removed.

Fig. 10 is a horizontal section on the line 10—10 of Fig. 7, looking in the direction of the arrows, with parts removed.

Fig. 11 is a fragmental detail, enlarged, showing 10 the drive from the motor.

Fig. 12 is a side elevation, partly in section, showing the means for supporting a stack of blanks, the means for picking the uppermost blank from the stack, the means for stripping a 15 blank from the picker, and the operating mechanism for the picker and stripper.

Fig. 13 is a top plan of the blank picker.

Fig. 14 is a bottom view of the blank picker.

Fig. 15 is a front elevation of the blank picker.

20 Fig. 16 is a plan of the blank stripper.

Fig. 17 is a plan of one of the blanks for forming a cup.

Figs. 18, 19, 20, 21, 22, 23, 24 and 25 are diagrammatic views showing different positions of 25 the blank picker and stripper, blank transfer member, or conveyor and cup forming mechanism.

Fig. 26 is a side elevation of the adhesive applying mechanism and driving means therefor.

30 Fig. 27 is a section through the adhesive or glue pot and applying roller.

Fig. 28 is an enlarged detail showing a portion of the cup forming mechanism, operating mechanism therefor, and means for removing and delivering the formed cups, with operating mechanism therefor.

Fig. 29 is a top plan of the blank transfer mechanism or conveyer with a portion of the forming plunger shown in horizontal section.

40 Fig. 30 is a detail showing a section through the initial blank folding mechanism with the forming plunger positioned with the blank folded into engagement therewith.

Fig. 31 is a top plan, with parts broken away, 45 showing the blank folding mechanism with the forming plunger omitted.

Fig. 32 is a side elevation of the mechanism shown in Fig. 31.

Fig. 33 is an end elevation of the mechanisms 50 shown in Figs. 31 and 32.

Figs. 34 and 35 are details showing side folding arms with the forming plunger shown in horizontal section in different vertical positions, Fig. 34 showing the initial fold of the blank to provide 55 the over-lapped edge portions while Fig. 35 shows the final folds of the edge portions with the over-lapped edges secured together.

Fig. 36 is a detail showing the forming plunger positioned in a female forming die or pocket with 60 the formed cup in position.

Fig. 37 is a side elevation of the forming plunger.

Fig. 38 is a transverse vertical section through the forming plunger on the section 38—38 of 65 Fig. 37.

Fig. 39 is a horizontal section through the forming plunger on the line 39—39 of Fig. 38.

Fig. 40 is a side elevation of the rotatable member carrying the female forming dies or pockets 70 with parts of the face plate thereof broken away.

Fig. 41 is a horizontal section on the line 41—41 of Fig. 40.

Fig. 42 is a detail showing a side elevation of a heating unit carried by the rotatable member.

75 Figs. 43 and 44 are details showing sections

taken through one of the female forming dies or pockets, Fig. 44 being taken on a section at right angles to that of Fig. 43.

Fig. 45 is a detail showing a side elevation of a member for removing the formed cups or receptacles from the female forming dies or pockets.

Fig. 46 is a horizontal section on the line 46—46 looking in the direction of the arrows.

Fig. 47 is a section on the line 47—47 of Fig. 46 10 looking in the direction of the arrows.

Fig. 48 is a detail showing a section on the line 48—48 of Fig. 10.

Fig. 49 is a detail showing a plan of the air controlled valve.

Fig. 50 is a section on the line 50—50 of Fig. 52.

Fig. 51 is a section on the line 51—51 of Fig. 50 looking in the direction of the arrows.

Fig. 52 is a section on the line 52—52 of Fig. 49 looking in the direction of the arrows; and

Fig. 53 is a section on the line 53—53 of Fig. 50 looking in the direction of the arrows.

In Figs. 1 to 4 inclusive of the drawings I have illustrated the supporting frame structure of my improved machine with the operating parts of 25 the machine removed for the purpose of clearness in showing the frame structure per se. The sup-

porting frame structure includes a base *a* to which is secured vertically extending side plates *b* and *c* by means of bolts *d* or other suitable fastenings. 30

The side plates, in turn, are connected by means of suitable cross members or braces which will be later described in connection with the operating parts of the machine. Secured to the rear edges of the side plates *b* and *c*, by means of the bolts 35

e or other suitable fastenings is an upwardly extending bracket member indicated generally at *f*, said bracket including side portions and forwardly directed arms *g* to which is secured a vertically extending member *h* having the horizontally 40 extending vertically spaced arms *i* and *k* extending from one side and the horizontally extending vertically spaced arms *l* and *m* extending from the opposite side as more clearly illustrated in Figs. 1 and 4 of the drawings. Secured 45 to the side portions of the bracket *f* are the plates *n* and *o*, the plate *n* having the depending vertically extending arm *p* while the plate *o* has the depending vertically extending arm *q*. It will be understood that I have only described the major 50

portions of the supporting frame structure and such frame structure includes supporting and bearing members or portions which will be later described in the detailed description of the construction of the machine and the operation 55 thereof.

The cups adapted to be formed by my machine are folded from paper blanks of single-piece construction, a detail of one of the blanks being shown in Fig. 17 of the drawings. Each of the 60 blanks is of a shape or configuration to provide the oppositely directed sectors or keystone-shaped portions *1* and *2*, a flange or extension *3* being formed on one longitudinal edge of the portion *1* while a flange or extension *4* is formed on the opposite longitudinal edge of the portion *2*. In forming the receptacles or cups, as will be later brought out in detail, the blanks are adapted to be initially folded on the transverse or horizontal center line and then the flanges *3* and *4* are folded to provide overlapped side seams as shown more particularly in Figs. 34, 35 and 36 of the drawings. When the individual receptacles or containers are completed they are of wedge-shape with a 75

substantially rounded normally open upper end and a relatively flat closed bottom.

The blanks used in the formation of the receptacles or containers are arranged in stacks and, as shown more particularly in Fig. 9 of the drawings, I preferably employ two stacks of the blanks and the blanks of one stack are arranged with the flanges or extensions 3 and 4 extending in opposite directions to the flanges or extensions 10 of the blanks in the other stack. By this arrangement when the containers or receptacles are formed those formed from the blanks of one stack will have their overlapped side seams folded and extended in opposite directions to the overlapped side seams of the receptacles or containers formed from the blanks of the other stack. By this arrangement the completed receptacles or containers may be nested or stacked as illustrated, described and claimed, in my Patent No. 1,972,007, dated August 28, 1934. As the construction of the support for the blanks of each stack, the mechanism for folding the blanks into cup formation, the mechanism for transferring the blanks from each stack to the folding or forming mechanism, and the delivery mechanism for the completed cups or containers, is the same in each instance, the same reference characters will be used for describing the supports for the blanks of each stack as well as the mechanism operating on the blanks taken from each stack for forming the completed cups or containers.

Stacks of paper blanks indicated at 5 are supported on tables or plates 6 and depending from each table or plate is a rack bar 7 which is slidably mounted in the bearings 8 and 9, as shown more particularly in Fig. 12 of the drawings, these bearings 8 and 9 forming part of the horizontal cross members 10 and 11 positioned between and secured to the inner faces of the side plates b and c of the supporting frame structure. Meshing with the teeth of the rack bars 7 are the transversely spaced gears 12 for raising and lowering the rack bars and blanks supported on the tables or plates 6. An angle iron cross member 13 is secured to the forward edges of the plates b and c of the supporting frame structure and secured to the top of this angle iron member by means of bolts 14 or other suitable fastenings are the four transversely spaced inwardly directed arms 15 formed on their inner ends with a vertical extension 16 the inner edges of which are dished or concaved for a purpose which will be later brought out. A transversely extending plate 17 is carried by the inwardly directed arms 18 of the bracket f of the supporting frame structure, this plate 17 being slightly spaced from the rear edges of the vertically extending side plates b and c as shown more particularly in Fig. 2 of the drawings.

Secured to the under face of the plate 17, by means of the bolts 19 or other suitable fastenings, are the four transversely spaced inwardly directed arms 20, each of the arms having a vertical extension 21 formed on its inner end, as shown more particularly in Fig. 12 of the drawings, the inner faces of the extensions 21 are dished or concaved for a purpose which will be later brought out. Supported by each of the arms 15 is a post or rod 22, the lower ends of the posts or rods being received in the dished or concaved portions of the extensions 16 and secured thereto by means of the pins 23. Supported by each of the arms 20 is a post or rod 24, the lower ends of the rods or posts being received in the dished or concaved portions of the extensions 21 and secured thereto

by means of the pins 25. Each of the posts or rods 22 and 24 is provided with a vertically extending groove or recess 26, as shown more particularly in Fig. 9 of the drawings. As also shown more particularly in this figure the rods or posts 22 and 24 are arranged in pairs to provide guides for the two stacks of blanks, the rods or posts 22 and 24 being so positioned that the longitudinally extending recesses or grooves 26 of each pair of rods or posts face one another so that the ends of the blanks may be received in said grooves or recesses 26, as shown in Fig. 9. Secured to each of the rods or posts 22 is an outwardly directed arm 27 having a depending extension 28 through which a pin 29 extends for securing the arm to the post or rod. Secured to each of the posts or rods 24 is an outwardly directed arm 30 having a depending extension 31 secured to the post or rod by means of a pin 32. It will be understood that these arms are arranged in pairs the same as the arms 15 and 20 and the inner faces of the extensions 28 and 31 are dished or concaved in the same manner as the extensions 16 and 21 and as shown more particularly in Fig. 9 of the drawings. By forming these extensions 16, 21, 28 and 31 with the dished or concaved inner faces the table or plate 6 and the blanks carried thereby may be moved vertically without interference. Carried by the four arms 27 and secured thereto by means of bolts 33 or other suitable fastenings is a transversely extending plate 34 to which is secured, by means of bolts 35 or the like, the angle iron members 36, one of these members 36 being positioned adjacent the longitudinal center line of each stack of blanks and carrying a spring finger 37 which overlies the uppermost blank of the stack as shown more particularly in Fig. 12 of the drawings. Carried by the four arms 30 and secured thereto by means of the bolts 38 or other suitable fastenings is a plate or strip 39 to which are secured by means of the bolts 40 or other suitable fastenings the angle iron members 41, these angle iron members 41 being positioned in line with the angle iron members 36 and each carrying a spring finger 42, the ends of which overlie the uppermost blanks of the stacks. It will be understood that these spring fingers 37 and 42 hold the blanks in proper position and in close engagement or contact in the stack and when the uppermost blank is removed the fingers snap over the next blank in the stack to hold the same in position.

Each of the gears 12, which mesh with the racks 7, is carried by a shaft 43 which is mounted in a bearing or bushing 44, the bushings being received in openings 45 formed in the side plates b and c. Loosely mounted on each of the shafts 43 is a worm gear 46 with which meshes a worm 47 carried by a shaft 48, the shaft 48 being mounted in bearings 49 carried by a plate 50 secured to a side plate of the supporting frame structure, as shown more particularly in Fig. 2 of the drawings, each of the plates 50 has an opening in register with the openings 45 through which the shafts 43 extend. Secured to one face of each of the worm gears 46, by means of the screws 51 or other suitable fastenings is a ring 52 having teeth on its outer face which are adapted to be engaged by teeth formed on a plate or ring 53 also loosely mounted on the shaft 43. The shaft 43 has a circumferentially extending groove 54, as shown more particularly in Fig. 48 of the drawings, and received in this groove is a ring 55 which bears against an inner face of the plate or ring 53 while a washer 56

is positioned between the inner face of the ring or plate 53 and the end of the hub of the worm gear 46. Keyed to the shaft 43 but adapted for longitudinal movement thereon, is a sleeve 57 the inner end of which bears against the outer face of the ring or plate 53 while the outer end is formed with a hand wheel 58 and a recess 59 in which is positioned a coiled spring 60 which surrounds the end of the shaft 43. The outer end of the coiled spring 60 bears against a plate 61 secured to the end of the shaft by means of the screw 62 or other suitable fastenings. Connected to each of the shafts 48 is a ratchet wheel 63 and a pawl 64 is normally in engagement with the teeth of each of the ratchet wheels. Each of the pawls 64 is carried by a member 65 adapted for rotary or oscillating movement on the shaft 48 and the members 65 are each provided with a laterally extending projection 66 to which one end of a depending rod 67 is pivotally connected as shown more particularly in Figs. 5 and 12 of the drawings. The opposite end of each rod 67 is connected to a head or block member 68 which is slidably mounted in an elongated opening 69 formed adjacent one end of a lever 70, as shown more particularly in Fig. 12 of the drawings. The normal position of the head or block member may be adjusted in the opening 69 through means of the screw 71. Each of the levers 70 is pivotally mounted on a stub shaft 71 supported by the inwardly extending bosses 72 formed on the inner faces of the side plates *b* and *c*. Carried by each of the levers 70, and positioned inwardly of the end opposite to that having the opening 69 is a roller 73 which engages the edge of a cam 74, said cam being keyed to the main drive shaft 75, as shown more particularly in Fig. 12 of the drawings, the main drive shaft being rotatably mounted in the bearings 76 on the side plates *b* and *c*, these bearings being illustrated more particularly in Figs. 2 and 3 of the drawings. Also keyed to the drive shaft 75 is a sprocket wheel 77 around which operates a drive chain 78 which in turn is driven through the motor 79 from a sprocket wheel connected to the motor shaft 80, the sprocket wheel being hidden behind the guard casing 81 shown in Fig. 6 of the drawings. The rollers 73 on the levers 70 are held in contact with the cams 74 by the coiled springs 82, one end of the springs being connected to the levers adjacent that end having the screw 71 while the opposite ends are connected to the base *a* of the frame as shown at 83 more particularly in Fig. 5 of the drawings.

55 From the above description it is thought that the manner of supporting and feeding the blanks from which the containers or cups are made will be understood. As the machine is being operated the stacks of blanks will be fed upwardly automatically so that they will be properly positioned to be removed by a picker to be later described. The main shaft 75 is operated through means of the chain 78 from the motor and as the main shaft is rotated the cams 74 will likewise be rotated to operate the levers 70 the operation of the levers 70 in turn raise and lower the rods 67 and as the rods are raised they will swing the members 65 and the pawls 64 engageable with the ratchet wheels 63 will rotate the shafts 48 and turn the worms 47. The worms 47 will rotate the worm wheels 46 which in turn will rotate the rings or plates 53 which being in frictional engagement with the ends of the sleeves 57 will rotate these sleeves. As these sleeves 57 are keyed to the shafts 43 they will rotate these

shafts with the gears 12 and as the gears 12 mesh with the rack bars 7 they will raise the plates or tables 6 containing the stacks 5 of the blanks. It will be seen that the tables or plates 6 with the stacks are raised by a step-by-step movement but when it is desired to quickly raise or lower the rack bars, such as when it is desired to replenish the stacks, or adjust the heights thereof, the hand wheels 58 may be grasped and the sleeves 57 slid longitudinally of the shafts 43 against the action of the coiled springs 60. When thus slid on the shafts 43 the hand wheels 58 and sleeves 57 may be rotated and in turn rotate the shafts 43 independent of the worm gears 46. Due to the frictional engagement between the ends of the sleeves 57 and the faces of the rings or plates 53 the worm gears 46 may be allowed to slip should for any reason the raising of the rack bars be obstructed. This will prevent breakage of parts as can readily be appreciated.

20 For removing the uppermost blanks from the stacks and delivering them to a transfer member which carries them to the forming mechanism to be later described, I provide what might be termed pickers which are generally indicated at A there being a picker in alignment with each of the stacks. Associated with each of the pickers is what might be termed a stripper indicated generally at B these strippers removing the blanks from the pickers for deposit on the transfer member to be later described.

25 Each of the pickers includes a plate 84 of the shape shown more particularly in Fig. 13 of the drawings and formed on and projecting from the upper surface of each of the plates are a pair of spaced flanges 85 each of which has an inwardly directed portion 86 forming a dovetail guide to receive a head portion 86' formed on the lower end of a vertically extending sleeve 87 as shown more particularly in Fig. 12 of the drawings. 30 On its bottom surface each of the plates 84 is formed with the depending flanges or lips 88 arranged as shown more particularly in Fig. 14 of the drawings, these flanges or lips being adapted to receive an adhesive in a manner to be later described so that as the pickers are lowered the flanges or lips 88 will be brought into engagement with the extensions 3 and 4 of the uppermost blank of a stack of such blanks and the adhesive, engaging the blank, will cause the same 35 to be carried by the picker as the same is raised. Each of the plates 84 is formed with the openings 89, 90, 91 and 92 for a purpose which will be later brought out. Each of the strippers associated with a picker includes a perforated plate 93 having a central opening 94 and a laterally extending arm 95 provided with an opening 96. The stripper plates are normally positioned as shown more particularly in Fig. 12 of the drawings on a plane slightly above the bottom edges 40 of the flanges or lips 88 of the picker plates 84. Secured in the opening 94, of each of the plates 93, is an upwardly extending rod 97 which extends through the sleeve 87 of the associated picker and is slidably mounted therein. Secured 45 to the upper end of each of the rods 97 is a laterally extending arm 98 to which is pivotally connected at 99 a depending link 100, the lower end of which is pivotally connected at 101 to a lever 102 loosely mounted on a shaft 103 mounted 50 in the bearings 104 of the side plates *b* and *c*, of the supporting frame structure. Pivotally connected at 105 to the opposite end of each of the levers 102, is a depending rod 106 having its lower end pivotally connected at 107 to the end 55

of a lever 70, previously described, the lever 70 being operated by a cam 74. It will thus be seen that as the cam 74 operates or rotates it in turn operates the lever 70 and through means of the connections just described raises and lowers the rod 97 which carries the stripper plate 93. Also loosely mounted on the shaft 103 is a lever 108, formed on its inner end with the spaced arms as shown more particularly in Fig. 8 of the drawings, an arm being associated with each of the picker sleeves 87. As shown more particularly in Fig. 12 of the drawings the end of each arm is forked as shown at 109 and engageable with pins or projections 110 extending laterally from the sleeve. The opposite end of the lever is pivotally connected to a depending rod 111 the lower end of said rod 111 extending through an opening formed in a member 112 and being slidably therethrough. A nut or collar 113 is received on the lower end of the rod 111 for connecting the rod to the member 112 and preventing disengagement thereof. Formed on the rod 111 is a collar 114 and interposed between this collar 114 and the member 112 is a coiled spring 115 which surrounds the rod 111 and normally holds the upper face of the nut 113 into engagement with the member 112 as shown more particularly in Fig. 12 of the drawings. The member 112 is pivotally connected at 116 to an arm or lever 117 which in turn is pivotally connected at 118 to the horizontal cross member 11, this being also clearly shown in Fig. 12 of the drawings. The arm or lever 117 carries a roller 119 which operates in a cam groove 120 formed in one face of a disc or wheel 121. The disc or wheel 121 is mounted on the main shaft 75 and as the shaft is rotated the disc or wheel 121 will in turn rotate and through means of the roller 119 engaged in the cam groove 120 the rod 111 will be raised and lowered to in turn swing the lever 108 on the shaft 103 to thereby raise and lower the pickers for the purpose previously set forth. It will be seen that by having the end of the rod 111 slidably connected with the member 112 there may be a movement of the lever 117 and member 112 relative to its associated rod 111 for a purpose which will be later brought out.

Secured in the opening 91 of each of the plates 84 of the pickers is a bracket 122 and pivotally connected to each of the brackets at 123 is an arm 124 one end of the arm being forked at 125 to engage around a pipe 126 which passes through the opening 92. On the opposite end of the arm 124 is an adjustable screw 127 for a purpose to be later brought out. Secured to the upper end of each of the pipes 126 is a coupling 128, while at the lower end of each of the pipes is a suction nozzle 129. Received on each of the pipes 126 are the nuts 130 which may be adjusted to control the position of the end of the arm 124. Surrounding each of the pipes 126, between the plate 84 and nozzle 129, is a coiled spring 131 which has a tendency to force the nozzle 129 downwardly. When the pickers are in their raised positions the adjusting screws 127 will contact with the forwardly directed flange 132 formed on the member 8 of the frame structure. When thus contacted that end of the arm 124 engaged with the nuts 130 will be in raised position as shown more particularly in Fig. 18 of the drawings with the vacuum nozzle 129 raised above the plane of the lower edges of the flanges or ribs 88 of the picker plate 84. When the picker is lowered, as shown more particularly in Fig. 20 of the drawings, the screw 127

will be removed from engagement with the flange 132 and the nozzle 129 will be lowered by the coiled spring 131 to engage with the uppermost blank of the stack and the arm 124 will be swung into position shown more particularly in Fig. 20 of the drawings. When the picker is again raised the screw 127 will be engaged with the flange 132 and raise the nozzle 129, and associated parts, against the action of the spring 131 into its original position shown in Fig. 18.

Connected to each of the couplings 128, carried by the pipes 126, is a flexible pipe 133 the two pipes leading to a T-coupling 134, as shown more particularly in Fig. 5 of the drawings, to which is connected a pipe 135, as shown more particularly in Fig. 6 of the drawings, the opposite end of the pipe 135 being connected to a pipe 136 by means of the coupling 137, the pipe 136 leading downwardly and connected to a horizontal pipe 138 through means of a coupling 139. The pipe 138, in turn, is connected to a pipe 140 by means of the coupling 141 and being in direct line with the pipe 142 which leads to a vacuum source not disclosed. In turn the pipes 140 and 142 are connected to a valve casing 143 by means of a T-coupling 144. However, it will be understood that there is a direct vacuum through the pipe 142 to the pipe 140 and such direct vacuum is not controlled by the valve within the casing 143.

The detailed operation of the pickers and strippers will be later described in connection with the mechanism for transferring the blanks to the forming mechanism.

Secured in the opening 96, of the laterally extending arm 95 of the stripper plate 93, is the lower end of a rod 145 which passes through the opening 90 in the picker plate 84 and acts as a guide for holding the stripper plate 93 relative to the picker plate 84. The position of this rod is more particularly illustrated in Figs. 18 and 20 of the drawings.

As previously set forth adhesive is to be applied to the bottom edges of the flanges or lips 88 of the picker plates 84 so that as the flanges or lips are brought into engagement with the uppermost blanks of the stacks adhesive will be applied along the flanges 3 and 4 of the blanks, it being noted more particularly by reference to Figs. 14 and 17 of the drawings that the flanges or lips 88 are arranged at an angle corresponding to the angles of the side flanges 3 and 4 of the blanks. An adhesive or glue receptacle is shown at 146 and in the sides of the receptacle is rotatably mounted a roller 147 including a central shaft portion 148, one end of the shaft projecting beyond one of the sides of the receptacle to receive a gear wheel 149, shown more particularly in Fig. 26 of the drawings. A removable cover plate 150 is supported on the receptacle. Also carried by the receptacle and supported by the upper edges of the sides thereof is a transversely extending bar 151 to which is secured, by means of the screws 152 or other suitable fastenings, a scraper plate 153 the lower edge of which is positioned in engagement with the roller 147 as shown more particularly in Fig. 27 of the drawings for removing excess or surplus glue or adhesive therefrom. The screws 152 pass through slightly elongated openings formed in the plate 153 so that the plate may be adjusted by means of the screws 154 which pass through a horizontal flange 155 formed on the upper edge of the plate 153, and engage the upper surface of the transversely extending strip or bar 151. The glue or adhesive receptacle 146 is formed on its bottom surface with the longitudi- 75

nally spaced castings 156 each of which is provided with a depending projection 157. The receptacle 146 is supported by the forwardly extending lugs or projections 158 formed on the plate 5 159 secured to the side plates *b* and *c* of the frame structure by means of the screws 160 or other suitable fastenings. The castings 156 are received on the lugs or projections 158 and each of the lugs or projections is formed in its upper face 10 with a recess 161, which recesses receive the depending projections 157 of the castings. The receptacle 146 is secured in position by means of screws 162 which pass through openings in a forwardly directed flange 163 formed on the plate 15 159 and through openings 164 in the lugs or projections 158 and into screw threaded openings formed in the bottom of the projections 157 of the castings 156. The screw rods 162 are provided with wings 165 so that the rods may be screwed 20 into or out of engagement. That end of the shaft 148 which carries the gear wheel 149 extends into and through a bearing indicated at 166 and receives on its end a hand wheel 167 whereby the shaft and roller 147 may be given a turn by hand 25 to free the same should it become stuck in the adhesive or glue. A scraper blade 168 is supported on the rear edge of the receptacle 146, as shown more particularly in Fig. 27 of the drawings to scrape surplus glue or adhesive from the 30 roller 147. The direction of rotation of the roller 147 is indicated by the arrow in Fig. 27. Lock nuts or collars 169 are received on the screw rods 162.

Secured to each of the sides of the bracket 35 member *f* by means of bolts 170 which pass through elongated openings 171 is a forwardly extending bar 172, the forward ends of the bars being supported by the L-bolts 173 which are supported from and extend through openings 40 formed in the arms 174, these L-bolts are connected to the arms by means of the nuts 175 and 176 positioned on opposite faces of the arms as shown more particularly in Figs. 5 and 26 of the drawings. Slidably mounted on each of 45 the bars 172 is a casting 177 which castings support and form bearings for a rod 178 carrying a roller 179, which roller is adapted to be engaged with the adhesive roller 147 and receive adhesive therefrom for application to the flanges or lips 88 of the picker plate 84. As shown 50 more particularly in Fig. 26 of the drawings the shaft rod 178 is removably connected to the castings 177 by the detachable plates 180, each of the plates 180 having connected thereto a threaded rod 181 which extends through its associated casting and receives a thumb nut 182. Pivotsly connected at 183, to each of the castings 177, is a link 184, the opposite end of the link being pivotsly connected at 185 to an arm 186 carried 55 by the shaft 187 rotatably mounted in the bearings 188 formed in the sides of the bracket *f* adjacent the lower end thereof, as shown more particularly in Figs. 2 and 3 of the drawings. One of the arms 186 is formed with an extension 189 to which is pivotsly connected at 190 a depending rod 191 having its lower end pivotsly connected at 192 to a lever or arm 193 carried by the shaft 118. Mounted intermediate the ends of the arm or lever 193 is a roller 70 194 which is adapted to be engaged by a cam 195 carried by the shaft 75. The arm or lever 193 is drawn downwardly, so that the roller 194 always contacts with the cam 195 by means of the coiled spring 196. Also mounted on the end 75 of the shaft 75 is the rotatable valve 197 which

operates in the valve casing or housing 143 previously described and connected to the outer face of the rotatable valve is an arm 198 which is operable, in a manner to be later described, for controlling an air supply to a discharge chute. 5

The shaft 148, carrying the adhesive roll or roller 147, is adapted to be continuously rotated as the machine is in operation in the following manner: Mounted on the drive shaft 75, which is rotated through the drive chain 78, by the 10 rotor is a sprocket wheel 199 and supported in the bearings 200 and 201 respectively of the side plates *b* and *c* of the frame structure are the shafts 202 and 203 the shaft 202 carrying a gear wheel 204 meshing with a similar gear wheel 205 carried by the shaft 203. The shaft 203 also carries a sprocket wheel 206, while the shaft 202 carries a sprocket wheel 207. A sprocket chain 208 is trained around the sprocket wheels 199 and 206 and a sprocket chain 209 is trained 15 around the sprocket wheel 207 and a sprocket 210 carried by the shaft 211 rotatably mounted in the forwardly extending bearings 212 and 213 carried by a plate 214 connected to the forward edges of the side plates *b* and *c* of the supporting 20 frame structure by means of the screws 215 or other suitable fastenings. Loosely mounted on the shaft 211 is a sprocket wheel 216 to the 25 face of which is secured a ratchet wheel 217 adapted to be engaged by the spring held pawl 218 carried by the arm 219 secured to the shaft 211. A stub shaft 220 is mounted in the bearing 221 and secured to this shaft are longitudinally spaced sprocket wheels 222 and 223. A 30 sprocket chain 224 is trained around the sprocket 35 wheels 216 and 223 while a sprocket chain 225 is trained around the sprocket wheels 222 and 149. A chain tightener including the arm 226 secured to the side plates *c* of the frame structure by means of the bolts 227 or other suitable 40 fasteners and the roller 228 as shown in Fig. 11 of the drawings for holding the sprocket chain 208 taut. For the driving mechanism just described attention is more particularly directed to 45 Figs. 11 and 26 of the drawings.

From the above detailed description of the glue or adhesive receptacle and associated parts it is thought that the manner of applying the adhesive or glue to the flanges or ribs of the picker plate will be understood. During the 50 operation of the machine the adhesive or glue applying roller 147, in the receptacle 146, will be rotated through the chain and gear mechanism described it being understood that the pawl 218, engaging the ratchet wheel 217, will rotate the 55 sprocket wheel 210. When the glue or adhesive is cold the roller 147 may be loosened by operation of the hand wheel 167, the sprocket wheel 216 being turned in a direction opposite to its roller operation to permit the pawl to slide around the ratchet wheel 217. When the castings 177 have been slid upon the bars 172 to their extreme forward positions the roll 179 will contact with the liquid or glue applying roll 147 and receive glue or adhesive therefrom. Then as the 60 castings 177 are moved rearwardly on the bars 172 the roll 179 will pass beneath the picker plates 84 and the roll 179 will engage the bottom edges of the flanges or lips 88 carried by the picker plates, applying adhesive thereto, 65 which adhesive will be applied to the blanks when the picker is lowered to engage the flanges or lips therewith. The castings 177 are operated on the bars 172 by engagement of the cam 195 with the roller 194 of the arm or lever 193 which 70 75

rotates the shaft 187 through means of the connection 191. The arms 186 are rigidly secured to the shaft 187 so that when the shaft is rotated the arms 186 will be swung to move the castings 177 through means of the link connections 184. In Fig. 26 of the drawings the castings 177 are shown in their forwardmost positions while in dotted lines the parts are shown in their rearwardmost positions.

For transferring the blanks from the pickers to the folding mechanism I provide reciprocating plates or carriers which are operable to a position beneath the pickers where they receive blanks therefrom and are then moved to position relative to the folding mechanism. Secured to each of the side plates *b* and *c* of the supporting frame structure, by means of screws 229 or other suitable fastenings is a pair of plates 230 each of which has a laterally extending arm 231 which is formed on its outer end with an upwardly extending bearing ear 232. Formed in the top edge of each of the arms 231 is a notch 233 and formed along each bottom edge is an inwardly directed flange 234 to support a folding assembly to be later described. Supported by the bearing ears 232 are the horizontal rods 235 which are also supported intermediate their ends by bearings 236. The carriers or plates for transferring the blanks are slidably mounted on these rods 235 and each of the carriers includes a plate or body portion 237 having at opposite ends projecting ears 238 to which castings or boxes 239 are secured by means of bolts 240 or other suitable fastenings, it being understood that these castings or boxes have longitudinal openings therein through which the rods 235 extend. Each of the plates 237 is also provided with an inwardly extending cut-out portion 241 to permit operation of a folding plunger to be later described. Secured to the upper surface of each of the plates 237 are gauge members 242 which are adapted to engage one side edge of the blank and gauge members 243 which will engage the ends of the blank as shown more particularly in Fig. 29 of the drawings. Gauge members 244 are also secured to the plate and positioned relative to the gauge members 242 to readily allow a blank to drop therebetween, the distance between the gauge members 242 and 244 being somewhat greater than the width of the blank as also shown more clearly in Fig. 29. On opposite sides of the recess or notch 241 each of the plates is provided with a cut-out portion 245 for a purpose which will be later apparent. Pivotaly connected to each of the castings or boxes 239 is a link 246 and as shown more particularly in Fig. 9 of the drawings the links 246 connected to one of the carriers or plates extend in an opposite direction to the links connected to the other carrier or plate. The outer ends of the links 246 are pivotally connected to depending arms 247 secured to and carried by a shaft 248 mounted in openings 249 formed in arms 250 carried by the member *h* as shown more clearly in Figs. 1, 2 and 4 of the drawings. Secured to one end of each of the shafts 248 is a beveled gear 251 which meshes with the beveled gears 252 carried by the shaft 253 mounted in the openings 254 formed in the sides of the bracket member *j*. Secured to the shaft 253 is an arm 255, as shown more particularly in Fig. 7 of the drawings and pivotally connected at 256 to the arm 255 is one end of a rod 257 having its lower end pivotally connected at 258 to one end of an arm or lever 259 pivotally connected on the shaft 11. Intermediate the

ends of the lever or arm 259 is a roller 260 which engages a cam 261 carried by the shaft 15. A coiled spring 262 has its upper end connected to the lever or arm 259 while its lower end is connected to the base *a* by means of an adjusting screw 263.

It will be seen that as the shaft 15 rotates it carries with it the cam 261 which operating against the roller 258 operates the rod 257 which in turn operates the shaft 253 and as the beveled gears 252 mesh with the beveled gears 251 on the shaft 248 the shaft 248 is swung to in turn swing the arms 247 which slide the carriers or plates 237 due to the link connection. In this manner, as has been previously stated, the carriers or plates 237 will be reciprocated on the horizontal rods 235 to be moved into position under the pickers or relative to the folding mechanism to be later described.

Supported on the inwardly directed flanges 234 of the plates 237, as shown more particularly in Fig. 7 of the drawings, and at each side of the machine as shown more particularly in Fig. 9 of the drawings are what might be termed folding or forming units indicated at *W*. Each of these units includes the top and bottom plates 264 and 265 vertically spaced by means of corner posts 266 to which they are secured by means of the screws 267 or other suitable fastenings. Each of the plates 264 and 265 is formed with an opening 268 of the shape shown more particularly in Fig. 31 of the drawings and secured to the upper surface of each of the top plates 264, adjacent one edge thereof, are the longitudinally spaced gauges 269 and 270 and secured at one longitudinal edge 35 of each of the plates by means of the screws 271 or other suitable fastenings, are the stops indicated at 272. Secured to the under face of each of the top plates 264, by means of the screws 273 or other suitable fastenings, and extending inwardly from each end thereof, are the bars or strips 274 each having an inwardly directed flange 275, these longitudinal bars or strips forming guides for slidably mounting the bars 276 each having pivotally connected at 277 to its inner end a plate 278 of the shape shown more particularly in Fig. 30 of the drawings, the upper edge of each of the plates being rounded as shown at 279 to be engaged by a plunger to be later described whereby the plates are separated and the bars 276 slid longitudinally. The bars 276 are normally held in their innermost position as shown more particularly in Figs. 31 and 32 of the drawings by means of the coiled springs 280 one end of each of the springs being connected to its associated bar 276 by means of a pin 281 while the opposite end is secured to a pin 282 carried by one of the bars or strips 274. Pivotally mounted on posts 283, carried by the bottom plate 265 of each of the folding units *W*, are the arms 284 to each of which is secured by means of the screws 285 or other suitable fastenings, a spring arm or plate 286 having its free end bent at an angle as shown at 287 for giving an initial fold to the side edges of a blank as shown more particularly in Fig. 34 of the drawings. Secured to the outer edge of each of the arms 284 is a plate 288 having a threaded opening to receive an adjustable screw 289 which will engage the edge of one of the bars or strips 274 to form a stop for the inward swinging movement of the arm 284 against the action of the coiled spring 290 one end of which is secured to a pin 291 carried by the base plate while the opposite end is connected to the arm. Pivotally connected to the posts 292 carried by 75

each of the bottom plates 265 of the unit W is an arm 293 formed on its inner end with an enlargement 294 which is downwardly and outwardly inclined as shown more particularly in Figs. 30, 31 and 32 of the drawings to give what might be termed the final fold of the edges of the blank in forming the cup or receptacle as shown more particularly in Fig. 35 of the drawings. Carried by each of the arms 293, adjacent its outer end, 10 is an adjustable screw 295 as shown more particularly in Fig. 31 of the drawings, these screws being engageable with certain of the corner posts 266 to limit the inward swinging movement of the inner ends of the arms 293 against action of the coiled springs 296, one end of each of the springs being connected to a pin 297 carried by the arm 293 while the opposite end is connected to a pin 298 projecting upwardly from the bottom plate 265. As shown more particularly in Figs. 30, 15 20 and 31 of the drawings the plates 278, carried by the bars 276, the inner ends 287 of the plates or arms 286, and the enlargements 294 carried by the arms 293 are all positioned in line with the openings 268 formed in the top and bottom plates 264 and 265.

23 The folding or forming units W are so positioned as to underlie the transfer tables or plates 237 when the same are moved towards the sides of the machine and the blanks carried by the
24 transfer tables or plates will be positioned so that they may be engaged by a plunger, to be later described, and forced through the openings in the top and bottom plates 264 and 265 to be folded in a manner to be later described. As has been previously stated when a blank is placed upon the transfer table or carrier 237 it will be positioned between the gauges 242, 243 and 244 and when the transfer table or plate is moved over the folding or forming unit the gauge members 269 and
25 270 will engage edges of the blank and force the same over into tight engagement with the gauges 242 and 243, as shown more particularly in Fig. 29 of the drawings and in proper position to be engaged by the plunger, to be later described, and forced through the folding or forming unit.
26

At 299 I have indicated a pair of folding plungers which are adapted to be engaged with the blanks carried by the transfer tables or plates and positioned over the folding or forming units W to fold the blanks on their transverse medial line and to force them through the folding or forming units W and to deposit the formed receptacles or cups in pockets or female dies to be later described. There is a folding plunger 299 positioned for operation in connection with each of the folding or forming units W and the lower portions of the plungers are of wedge-shaped formation as shown more particularly at 300. Each of the folding plungers is recessed from its upper end to provide a seat 301 and openings 302 and 303, the openings 303 communicating with the vertically extending passageways or conduits 304 for a purpose which will be presently described. Received on the seat 301 of each of the plungers, and secured thereto by means of the screws 305 or other suitable fastenings is a plate 306 having a depending sleeve 307 received in the opening 302 as shown more particularly in Fig. 38 of the drawings. Received in a central opening in the plate and extending into the sleeve 307 thereof, is a tube or pipe 308, this pipe being secured to the sleeve 307 by means of a cross connecting pin 309 or other suitable fastenings and forming the plunger rod. Secured

within the sleeve 308, in any suitable manner, is a thimble or sleeve 310 to which is secured the lower end of an air conduit 311. Formed in the wedge-shaped portion 300, of each of the plungers, are a plurality of openings which extend from the side edges thereof as shown more particularly in Figs. 34, 35, 37, 38 and 39 of the drawings, and communicate with the passages 304. At 312 I have shown a line of relatively small openings communicating with each of the passages 304 and adjacent this line of openings is a shorter line of relatively larger openings indicated at 313. Spaced somewhat from the line of openings 312 are the openings 314 and 315 and it will be understood that the openings 313, 314 and 315 also communicate with the same passage 304 as do the openings 312. The pipe or tube 308, forming the plunger rod of one of the plungers, is slidably mounted in aligned openings formed in the arms *i* and *k* of the member *h* whereas the pipe or tube forming the plunger rod of the other plunger will be slidably mounted in aligned openings in the arms *l* and *m* of the member *h*. Secured to the shaft 103 are the arms or levers 316, the inner ends of these arms or levers being forked as shown at 317 to straddle the plunger rods 308, as shown more particularly in Fig. 8 of the drawings and formed in the forked ends are the elongated passages 318 in which operate pins or projections 319 carried by the plunger rods as shown more particularly in Fig. 28 of the drawings. Also secured to the shaft 103 is a sleeve or collar 320 having the outwardly extending arm 321 to which is pivotally connected at 322 the upper end of a rod 323, the lower end of the rod having slidable engagement with a yoke or member 324 as shown more particularly in Fig. 28. A collar or shoulder 325 is formed on or carried by the rod 323 and interposed between this shoulder or collar 325 and the yoke or member 324 is a coiled spring 326 which normally holds the head 327 on the lower end of the rod 323 into engagement with the surface of the yoke or member. This spring 326 provides for a yielding movement between the yoke or member 324 and the rod 323 to prevent breakage should any clogging occur. The yoke or member 324 is pivotally connected at 328 to an arm or lever 329 which in turn is pivotally mounted on the rod 108 carried by the member 11. Mounted intermediate the ends of the arm or lever 329 is a roller 330 which is operable in the cam groove 331 formed in a face of the disc or plate 121. It will be understood that this cam groove 331 is formed in that face of the disc or plate 121 opposite to that containing the cam groove 120. It will thus be seen that as the disc or plate 121 is rotated the rod 323 will be raised and lowered to in turn operate the extension 321 of the sleeve 320 and as this sleeve is secured to the shaft 103 it will in turn raise and lower the arms or levers 316 and thereby raise and lower the plunger rods 308 carrying the plungers 299. As the plungers are lowered they will engage the blanks and fold the same on their transverse medial line and then carry them through the folding or forming units *W* where the side edges are turned or overlapped as shown more particularly in Figs. 34, 35 and 36 of the drawings, the members 287 carried by the arms 284 initially folding edges of opposite side walls of the blank to engage the plunger and overlie the openings 312 and 313 formed in the wedge-shaped portion 300 of the plunger while the portions 294, carried by the arms 293 will fold the opposite edges of 75

the side walls of the blank to overlapped position shown more particularly in Fig. 35 of the drawings where the adhesive causes a securing thereof. Suction or air blast is created through the 5 passages or openings 312, 313, 314 and 315, in a manner to be later described, and when suction is applied or drawn in through the openings 312 and 313 draw the initial folds or bends of the blank into engagement with the plunger as shown 10 in Fig. 34 whereas suction through openings 314 and 315 draw the later folded or bent side edges into engagement with the plunger and in overlapped position as described. Connected to the air conduits 311, carried by the plunger rods 308, 15 is the flexible piping or hose 332, the inner ends of which are connected by the coupling 333 to the pipe 334 which extends downwardly and is connected by suitable couplings to the pipe 335 which in turn is connected to the valve casing 143 at 336. A pipe 337 for an air blast is connected to the valve casing 143 at 338 and a 20 vacuum pipe 339 is connected to the valve casing by the coupling 144. It will be understood that the air suction or blast will be controlled 25 by the rotatable valve 197 within the casing 143 and either suction or air blast may be created through the pipe 335 and associated pipe 334. When suction is created through these pipes suction 30 will likewise be created through the air conduits 311 to draw the blanks into engagement with the plungers as previously described and when air blast is created through the pipes and associated connections the formed cups or receptacles may be dislodged from the plungers into the 35 pockets or female dies to be later described.

Carried by the supporting frame structure and positioned at opposite sides thereof, are rotatable members or turrets which carry circumferentially spaced pockets or female dies into which 40 the completed cups or receptacles are deposited from the folding or forming plungers, one of the rotatable members or turrets being positioned beneath each of the folding or forming units W. The positions of these rotatable members or turrets are more clearly shown in Figs. 5, 6 and 7 of the drawings. Formed in each of the side plates b and c, of the frame structure, is a bearing opening 340 in each of which openings is supported a stub shaft 341 having an integral collar 342 which engages the surrounding wall of the bearing opening as shown more particularly in Fig. 41 of the drawings. A nut 343 is received on one end of the stub shaft and engages the opposite side of the wall of the bearing opening to 45 secure the end of the shaft therein. Received on the portion 344, of each of the stub shafts 341, are the roller bearings 345 which support the hub portion 346 of a plate 347 which plate is formed on its outer periphery with the concaved or dished portions 348 and on its outer face with the notches or recesses 349 for a purpose to be 50 later described. Secured to what might be termed the inner face of each of the plates 347, by means of the screws 350 or other suitable fastenings are 55 the circumferentially spaced female dies or pockets indicated at 351, more particularly in Figs. 40 and 41 of the drawings, and each of these female dies or pockets is formed at its inner end with an opening 352 and an enlarged threaded opening 353.

Secured in each of the threaded openings 353, by means of suitable couplings, is one end of a suction pipe 354 and the opposite ends of these suction pipes are received in openings formed 75 in the periphery of a ring-like member 355 sup-

ported and carried by the end of the hub portion 346 of the plate 347 as shown more particularly in Fig. 41 of the drawings. Each of the peripheral openings in which the ends of the pipes 354 are connected communicates with a lateral opening 5 356, which lateral openings extend to one face of the ring-like member. Received on the reduced portion 357 of each of the stub shafts 341 is a sleeve 358 to which is secured, by means of screws 359 or other suitable fastenings, a plate 10 360 which overlies an opening 361 formed in a plate 362 secured to certain of the female dies or pockets 351 by means of the screws 363 or other suitable fastenings which are received in threaded openings 364 formed in the sides of the dies 15 or pockets as shown more particularly in Fig. 40 of the drawings. The plate 360 is held in position by means of the nut 365 received on the threaded end 366 of the stub shaft, the nut bearing against a washer 367, as shown more particularly in Fig. 41 of the drawings. Secured to the plate 360, by means of the coupling member 368, is a casting 369 formed on its inner face with a semi-circular groove or recess 370 and forming communication between this semi-circular recess or groove and the coupling 368 is an opening 371. Connected to the coupling 368 of the two rotatable members or turrets is a suction pipe or hose 372 and the opposite ends of the suction hose or pipes are connected to the 20 coupling 373 which in turn is connected to the branch pipe 374 from the vacuum or suction pipe 339. It will thus be seen that suction or vacuum through the pipe 339 creates suction through the pipes or hose 372 which through the couplings 35 368 creates suction through the openings 371 and the semi-circular groove or recess 370. It will be understood that the plates 347 will be rotated, in a manner to be later described, and carry with them the female dies or pockets 351 40 and the ring-like member 355. While the closure plates 362 and 360 will be held stationary with the casting 369 and as the ring-like member 355 is rotated it will successively bring the lateral openings 356 into registration with the semi-circular groove or recess 370 and create suction 45 in those female dies or pockets connected to those lateral openings in communication with the semi-circular groove or recess while the other lateral openings are not in registration with the semi-circular groove or recess 370 will be cut off from said suction or vacuum. In Fig. 40 of the drawings I have shown the semi-circular groove or recess 370 in dotted lines with certain of the lateral openings 356 in communication therewith 50 while others are out of communication.

Secured to the inner face of the plates 360, by means of the screws 375, or other suitable fasteners, are the brackets 376 which have threaded openings into which heaters 377 are threaded, as 60 shown more particularly in Fig. 42 of the drawings, and connected to these heaters are the feed wires 378 which lead to the heater switch 379 which is connected through the wire 380 to the switch box 381. It will be seen that a compartment is formed between the plate 347 and plates 360 and 362 and the air within this compartment will be heated by the heaters 377, the heated air in turn heating the female dies or pockets 351 to dry out the adhesive for connecting the edges of the side walls of the completed cups or receptacles.

Secured to each end of the shaft 202 is a Geneva arm 382, as shown more particularly in Fig. 10 of the drawings, and each of these Geneva 75

arms has secured thereto a roller 383. As the shaft 202 is rotated, in the manner previously described, the rollers 383 will engage in the notches or recesses 349 of the plates 347 and rotate these plates and attached parts, the hub portions 384 of the arms engaging in the concaved or dished portions 348, as shown more particularly in Fig. 40 of the drawings. It is thus seen that the turrets or rotatable members formed by the plates 347 and associated parts will be intermittently rotated through means of the Geneva movement.

As has been previously brought out after the forming plungers 299 have carried the blanks 15 through the folding and forming units W they will continue their movement and the formed cups or containers will be permitted to drop therefrom into a female die or pocket of the rotatable member or turret. The formed cup or 20 container will drop into a pocket at the position indicated at 385 in Fig. 40 of the drawings and as the turret is rotated towards the left of this figure a suction or vacuum will be created in the die or pocket when it reaches the point 25 386 and such vacuum or suction will continue until the die or pocket reaches the point 387. Between the points 387 and 385 there is no vacuum or suction created and the completed cup or 30 container will be removed from the die or pocket when it reaches the point 388 in a manner to be later described. At the time that the formed cup or container is to be dropped from the forming plunger 299, into the female die or pocket, vacuum or suction through the 35 openings of the plunger is broken and an air blast substituted due to the rotation of the valve 197, the air blast passing into the casing 143 of the valve and through the passages in the valve to the connection 336 and through the pipes 335 and 342 40 into the connections 332 to the pipes 311 connected to the plungers, the air blast passing from the plunger through the openings 312, 313, 314 and 315. The air blast tends to free the formed cup or receptacle from the plunger and permits the same to drop into the female die or 45 pocket 351 in alignment therewith.

In Figs. 49 to 53 inclusive of the drawings I have shown the detailed construction of the air and vacuum controlled valve and casing therefor, the air line pipe 337 is connected to the casing at 389, the vacuum line 339 at 390 and the pipe 335 is connected at 336, as previously described. The valve 197 is formed with the circumferentially extending grooves 391, 392 and 50 393, the grooves 391 and 392 being connected by the longitudinal passage 394 while the grooves 392 and 393 are connected by the longitudinally extending passage 395. It will be understood that the passages will be placed in proper communication upon the rotation of the valve within the casing and a further detailed description thereof is not thought necessary at this time.

I have provided means for removing the completed cups or containers from the rotating members or turret when they reach the point indicated at 388 in Fig. 40 of the drawings. Secured to the outer face of each of the plates *n* and *o* forming a part of the supporting frame structure, by means of the bolts 396 or other suitable fastenings, is a frame 397, as shown more particularly in Fig. 8 of the drawings and these frames are of such a formation that the walls thereof are tapered downwardly and outwardly as shown at 398, more particularly in Fig. 6 of the drawings to provide a relatively narrow outer edge

or surface provided with the projecting ears or lugs 399 as shown more particularly in Fig. 2 of the drawings. Secured to these lugs 399, by screws or other suitable fastenings, of each of the frames 397, is a horizontal bar 400, the upper and lower edges of which project beyond the horizontal edges of the frame, as shown more particularly in Fig. 6 of the drawings, and receive a slide 401 having an outwardly directed flange 402 provided with a threaded opening to 10 receive a screw 403 for a purpose to be later described. Pivotally connected to each of the slides 401, at 404, is a link 405 which in turn is pivotally connected at 406 to the lower end of an arm 407 secured to a rod 408 mounted in the bearing 15 openings 409 of the plates *n* and *o*. Also secured to the rod 408, is an arm 410 to which is pivotally connected at 411 one end of a rod 412 which is formed at its lower end with a band or eye portion 413 in which operates an eccentric 414 20 carried by the shaft 202. Secured to each of the rods 400, and depending therefrom, is an arm 415 to which is pivotally connected at 416 one end of a link 417 having an elongated opening 418. Adjacent its lower or bottom edge each of 25 the slides 401 is formed with a threaded opening 419 in which is connected the end of a pipe 420 the opposite ends of which pipes are connected to the vacuum line or pipe 339 as is readily apparent by referring to Fig. 6 of the drawings. 30 Communicating with each of the threaded openings 419 is an opening 421 which communicates with a groove or recess 422 formed in the outer face of the slide as shown more particularly in Figs. 46 and 47 of the drawings. Connected to 35 the lower portion of the slide, by means of the bolt 423 and nut 424 is a swinging arm 425. Leading from the inner face of the arm, as shown more particularly in Fig. 46 of the drawings, is a passage 426 which communicates with the longitudinally extending passage 427, the passage 427 communicating through the angular passage 428 with the flexible suction cup 429. When the arm 425 is in the position shown in Figs. 45 and 46 of the drawings the passage 426 communicates 40 with the recess or groove 422 and therefore suction is created through the passages 426, 427 and 428 as will be readily apparent. When the arm 425 is swung into the position shown in Figs. 7 and 28 of the drawings the passage 426 will be 45 out of communication with the groove or recess 422 and there will be no suction through the passages of the arm. A coiled spring 430 is connected to the arm 415 and to the pin 431 formed on the angular extension 432 of the arm 425 50 and a pin 433 also carried by the angular extension 432 is received in the elongated opening 418 of the link 417. Normally the parts just described will be in the positions shown in Figs. 7 and 28 of the drawings, but due to the rotation of the eccentric 414 the rod 412 will be drawn 55 downwardly to swing the arms 407 inwardly of the position shown in Figs. 7 and 28 and this movement will operate the slides 401 into the position shown by dotted lines in Fig. 28. As the slides 401 are moved inwardly the pins 433 of the angular extensions 432 of the arms 425 will be disengaged from the end of the elongated opening 418 in the links 417 and the springs 430 will swing the arms 425 upwardly into the position shown in dotted lines in Fig. 28 and engage the vacuum cup 429 with the inner wall of the completed cup or receptacle within the female die or pocket of the rotatable member or turret. When in this position there will be suction 60

through the passages of the arms and as the movements of the slides are reversed towards their original positions by operation of the eccentric 414 the completed cup or receptacle will be withdrawn from the female dies or pockets into the position shown by dotted lines in Fig. 28. When in this position the vacuum through the passages of the arms 425 will be broken and the cup or receptacle will drop into and through the chute 434 for deposit into the trough 435. Intermittent blasts of air are discharged into the trough 435 through means of the pipes 436 and 437 shown more particularly in Fig. 6 of the drawings, the pipe 437 entering the trough adjacent the end where the cups or receptacles are deposited while the pipe 436 enters the trough intermediate the ends thereof. The pipes 436 and 437 are connected by the pipe 438 to the coupling 439 which in turn is connected to the air pipe 337 by the connection 440. Within the coupling 439 is a valve having a stem 441 adapted to be engaged by the arm 198 carried by the valve 197, as shown more particularly in Fig. 10 of the drawings. As the valve in the coupling is operated it permits intermittent puffs or blasts of air to be discharged through the pipes 436 and 437 to convey the cups or receptacles through the trough 435 from which they may be removed in any desired manner. Passage of air through the pipes 436 and 437 may be regulated through means of the turn valves 442 shown in Fig. 10. Swinging movement of the angular extension 432 may be limited by engagement with the adjustable screws 403 carried by the slides 401.

As has been previously stated in the brief description of the figures Figs. 18 to 25 inclusive show diagrammatically the different relative positions of the pickers and strippers, the transfer mechanism for the blanks, and the forming dies. In Fig. 18 I have illustrated what may be termed the normal or initial positions of the parts in which the picker and stripper and forming plunger are in their normal raised positions and the transfer table or plate contains a blank to be moved into the forming or folding zone. Fig. 19 shows the stripper in engagement with the top of the stack of blanks, the picker slightly raised from the blanks, and the transfer table or plate moved in position over the folding or forming unit with the forming or folding plunger still in raised position. Fig. 20 shows the picker moved down into engagement with the uppermost blank of the stack, the stripper still in engagement with the top of the stack and the forming or folding plunger engaged with the blank carried by the transfer table or plate but prior to being folded. Fig. 21 shows the stripper in raised position, the picker still in contact with the uppermost blank of the stack, and the forming or folding plunger moved downwardly into the forming or folding unit. Fig. 22 shows the picker and stripper in raised position with a blank, the transfer table or plate moving back towards the stack to receive another blank and the forming or folding plunger moved further downwardly through the folding or forming unit and into one of the female dies or pockets of the rotatable member or turret. Fig. 23 shows the transfer table or plate moved back over the stack with the stripper and picker lowered to deposit the blank shown in Fig. 22 and the folding or forming plunger moved downwardly to its extreme position in a female die or pocket of the rotatable member or turret. Fig. 24 shows the picker in raised position, the stripper having

disconnected the blank therefrom for deposit onto the transfer table or plate and the forming or folding plunger moved backward to its normal position, and Fig. 25 shows the parts returned to their normal positions of Fig. 18. From the above it is thought that the detailed construction and operation of the machine will be clearly understood. I have provided a machine adapted for forming complete cups or receptacles from blanks, and in the illustration I. 10 have disclosed a machine adapted for forming two sets or series of cups or receptacles from blanks arranged in two separate stacks, the blanks from one stack being transferred to folding or forming mechanism at one side of the 15 machine while the blanks from the other stack are transferred to folding or forming mechanism at the opposite side of the machine. The blanks of the formation shown more particularly in Fig. 17 of the drawings are arranged in 20 two stacks, as shown more particularly in Fig. 9 of the drawings and the uppermost blanks are removed from the stacks by the pickers having the adhesive applied thereto, the adhesive being transferred to the blanks so that overlapped 25 edge portions may be secured together. The pickers are provided with suction mechanism which aids in holding the blanks thereto and when the transfer tables or plates 227 are positioned beneath the pickers the blanks are removed from the pickers by means of the strippers and placed upon the transfer tables or plates between the gauges 242, 243 and 244 carried thereby. After receiving the blanks the transfer tables or plates are moved towards the opposite sides of the machine in the manner previously described and when they are moved over the forming or folding units W the blanks are engaged by the gauges 269 and properly held in 30 position for engagement by the forming or folding plungers 299. As the folding or forming plungers 299 are lowered they initially fold the blanks on their transverse medial lines as shown more particularly in Fig. 30 of the drawings and then as the plungers are further lowered they 35 carry the blanks through the forming or folding unit so that the side walls of the blank are folded around the wedge shaped portions of the plungers, side edges overlapped, and secured together. After being passed through the forming or folding units suction is removed from the plungers and an air blast substituted to loosen the formed cups or receptacles from the plungers and to permit them to drop into the female dies or pockets 35 of the rotatable members or 40 turrets. After dropping from the plungers, into the female dies or pockets, suction is applied to tightly draw the cups or receptacles into the pockets or dies. The turrets or rotatable members are heated in the manner previously set 45 forth and after the adhesive has dried, the completed cups or receptacles are removed from the female dies or pockets by the arms 425, operated in the manner previously described, and when removed from the dies or pockets the arms 425 50 are swung in such a manner as to permit the completed cups or receptacles to drop into the chutes 434 from which they are dropped into the trough 435 through which they are carried by air puffs or blasts intermittently discharged into 55 the chute. From the chute 435 the completed cups or containers may be removed in any suitable manner and be placed in suitable cartons or containers. While I have only illustrated, in the drawings, a single chute 435 it will be un- 60

derstood that two chutes may be employed, if desired, and as the receptacles or cups formed at opposite sides of the machine have their side seams extended in opposite directions the receptacles or cups formed at one side of the machine may be alternated in a stack with those cups or receptacles formed at the opposite side of the machine. This arrangement of stacking, as previously set forth, is disclosed and claimed in my 10 Patent No. 1,972,007, dated August 28, 1934.

Having fully described my invention, what I claim as new and desire to secure by Letters Patent is:—

1. A machine for making paper containers such as cups, including a folding unit, means for positioning a blank relative to the folding unit, and a wedge-shaped plunger having an edge portion adapted to engage the face of the blank intermediate its ends and to force the same into 15 and through the folding unit, said plunger in its movement folding the blank intermediate its ends and cooperating with the unit to shape the blank into a container.

2. A machine for making paper containers such as cups, including a folding unit, means for positioning a blank relative to the folding unit, and a plunger for moving the blank into the folding unit, said plunger having downwardly and inwardly tapered faces to provide an elongated edge portion to be engaged with the blank intermediate its ends, the movement of the plunger folding the blank intermediate its ends and cooperating with the unit to shape the blank into a container. 20

3. A machine for making paper containers such as cups including a folding unit, means for positioning a blank relative to the folding unit, a plunger engageable at the transverse medial line of the blank for moving the blank into the 25 folding unit and folding the same intermediate its ends to provide side portions, and means for creating suction through the plunger to draw the side portions of the blank into engagement therewith, said plunger and unit cooperating to shape 30 the blank into a container.

4. A machine for making paper containers such as cups, including a folding unit, means for positioning a blank relative to the folding unit, a plunger engageable at the transverse medial line of the blank for moving the blank into the folding unit and folding the same intermediate its ends to provide side portions, means for creating suction through the plunger to draw the side portions of the blank into engagement therewith, the plunger and unit cooperating to shape 45 the blank into a container, and means for creating an air blast through the plunger to free the formed container therefrom.

5. A machine for making paper containers such as cups, including a folding unit, means for positioning a blank relative to the folding unit, a plunger engageable at the transverse medial line of the blank for moving the blank into the folding unit for folding the blank intermediate its 50 ends to provide side portions, said plunger and unit cooperating to shape the blank into a container, and means for creating an air blast through the plunger to free the formed container therefrom.

6. A machine for making paper containers such as cups including means for supporting a stack of blanks, a member movable to remove the uppermost blank from the stack, means movable 55 relative to said member for removing the blank

therefrom; and means for shaping the blank into a container.

7. A machine for forming paper containers such as cups including means for supporting a stack of blanks, a member movable to remove the 5 uppermost blank from the stack, a second member movable with and relative to the first member for removing the blank therefrom, and means for shaping the blank into a container.

8. A machine for making paper containers 10 such as cups including means for supporting a stack of blanks, a member movable to remove the uppermost blank from the stack, a second member movable relative to the first member for removing the blank therefrom, and means for 15 shaping the blank into a container.

9. A machine for making paper containers such as cups including means for supporting a stack of blanks, a member movable to remove the uppermost blank from the stack, said member 20 including depending flanges, means for applying adhesive to the flanges, a second member movable to remove the blank from the first mentioned member, and means for shaping the blank into a container. 25

10. A machine for making paper containers such as cups including means for supporting a stack of blanks, a member having depending flanges, means for applying adhesive to the flanges, means for moving the member to engage 30 the flanges with the adhesive thereon with the uppermost blank of the stack to remove the same from the stack, a second member movable relative to the first member for disengaging the blank from the flanges thereof, and means for 35 shaping the blank into a container.

11. A machine for making paper containers such as cups including means for supporting a stack of blanks, a member for removing the uppermost blank from the stack, a second member 40 operable to remove the blank from the first mentioned member, means for operating the two members in unison and one relative to the other, and means for shaping the blank into a container.

12. A machine for making paper containers such as cups including means for supporting a supply of blanks, a folding unit, a member for transferring individual blanks from the supply to the folding unit, said transfer member and folding unit having cooperating gauge members 45 to position the blank, and means for moving the blank from the transfer member into the folding unit. 50

13. A machine for making paper containers such as cups including means for supporting a supply of blanks, a folding unit, a member for transferring individual blanks from the supply to the folding unit, said transfer member and folding unit having cooperating gauge members to position the blank, and a plunger operable to 55 engage the blank on the transfer member to move the same into the folding unit.

14. A machine for making paper containers such as cups including means for supporting a supply of blanks, a folding unit, a member for transferring individual blanks from the supply to the folding unit, said transfer member and folding unit having cooperating gauge members to position the blank, and means engageable with the blank for folding it on its transverse medial 70 line and moving the same into the folding unit, said folding unit cooperating with the means engageable with the blank for completing the shaping of the blank into a container.

15. A machine for making paper containers 75

- such as cups including means for supporting a supply of blanks, a folding unit, a member for transferring individual blanks from the supply to the folding unit, said transfer member and 5 folding unit having cooperating gauge members to position the blank, and a plunger engageable with the blank for folding it on its transverse medial line and moving the same into the folding unit, said folding unit cooperating with the 10 plunger engageable with the blank for completing the shaping of the blank into a container.
16. A machine for making paper containers such as cups from blanks including a folding unit, and a member engageable with a blank for 15 forcing the same into and through the folding unit, said folding unit including slidable members cooperating with the forming member to fold the blank upwardly into engagement with the forming member, and pivotally mounted 20 members engageable with the edges of the blank for overlapping the same to complete a container.
17. A machine for making paper containers such as cups from blanks including a folding unit, and a forming member adapted to engage 25 and force a blank into and through the folding unit, said folding unit including slidable members engageable with the blank and cooperating with the forming member to fold the blank on its transverse medial line to provide upwardly 30 extending opposite face portions, horizontal swinging members engageable with one edge of each face portion to fold the same around the forming member, and other members mounted for horizontal swinging movement engageable 35 with the opposite edges of the face portions to fold the same around the forming member and in overlapped relation to the previously folded edge portions.
18. A machine for making paper containers 40 such as cups from blanks including a folding unit, and a forming member adapted for forcing a blank into and through the folding unit, said folding unit including members cooperating with the forming member to fold the blank to provide upwardly extending opposite face portions and to overlap the side edges thereof, and the forming member including means for creating a suction to draw the blank into engagement therewith and an air blast to discharge the shaped 45 container therefrom.
19. A machine for making paper containers such as cups including a folding unit, means for positioning blanks relative to the folding unit, a rotatable member having circumferentially 50 spaced pockets, and a member adapted to force the blanks through the folding unit to shape the same into a container, overlapped edge portions of the container being connected by an adhesive, the shaped containers being successively received 55 in the pockets of the rotatable member, means for heating the rotatable member to dry the adhesive connecting the overlapped edges of the container, and means engageable interiorly of the container for positively removing the same 60 from the pockets.
20. A machine for making paper containers such as cups including a folding unit, means for positioning blanks relative to the folding unit, a rotatable member having circumferentially 65 spaced pockets, means for forcing the blanks into and through the folding unit to shape the same into containers having overlapped edge portions, the overlapped edge portions being connected by an adhesive and the containers being 70 successively received in the pockets of the ro-
- tatable member, means for creating suction in the pockets during a portion of the rotation of the member for tightly drawing the containers therein, means for heating the rotatable member for drying the adhesive connecting the overlapped edges of the containers, and means for successively removing the containers from the pockets, said means including a member engageable interiorly of the containers. 5
21. A machine for making paper containers 10 such as cups including means for shaping blanks into containers, a member adapted to receive the shaped containers, and a member separate from the shaping means operable to remove the containers from the receiving member, said member 15 engaging interiorly of the containers.
22. A machine for making paper containers such as cups including means for shaping blanks into containers, a member having pockets adapted to successively receive the shaped containers, 20 and a swinging arm adapted to be operated to engage interiorly of the containers and remove the same from the pockets.
23. A machine for making paper containers such as cups including means for shaping blanks 25 into containers, a rotatable member having spaced pockets to successively receive the containers, a swinging arm adapted to be operated to remove the containers from the pockets, and means for creating suction through the arm. 30
24. A machine for making paper containers such as cups including means for shaping blanks into containers, a rotatable member having spaced pockets to receive the shaped containers, an arm adapted to be operated to engage interiorly of a container within a pocket, means for creating suction through the arm to connect the container thereto, and means for breaking said suction to permit deposit of the container. 35
25. A machine for making paper containers 40 such as cups including means for shaping blanks into containers, a rotatable member having spaced pockets to successively receive the shaped containers, a slidable member including a swinging arm adapted to be operated to engage the 45 arm interiorly of a container in a pocket, means for creating suction through the arm to connect the container thereto, means for breaking the suction to permit deposit of the container, and a member adapted to receive the containers. 50
26. A machine for making paper containers such as cups including means for shaping blanks into containers, a rotatable member having spaced pockets to successively receive the shaped containers, a slidable member including a swinging arm adapted to be operated to engage the 55 arm interiorly of a container in a pocket, means for creating suction through the arm to connect the container thereto, means for breaking the suction to permit deposit of the container, a 60 member adapted to receive the containers, and means for carrying the containers through the last mentioned member.
27. A machine for making paper containers such as cups including means for supporting a 65 stack of blanks, a member movable to remove the uppermost blank from the stack, said member including depending flanges, a suction nozzle carried by the member, and means controlled by the movement of the member for raising and 70 lowering the nozzle relative to the flanges.
28. A machine for making paper containers such as cups including means for supporting a stack of blanks, a member movable to remove the uppermost blank from the stack, said member 75

- including depending flanges, means for applying adhesive to the flanges, a suction nozzle carried by the member, and means controlled by the movement of the member for raising and lowering the nozzle relative to the portions of the flanges containing the adhesive. 5
29. A machine for making paper containers such as cups including means for supporting a stack of blanks, a member for removing the 10 uppermost blank from the stack, said member having depending flanges, a second member normally positioned on a plane above the bottom edges of the flanges, and means for moving the members in unison to remove the uppermost 15 blank from the stack and to move the second member relative to the first member to a position on a plane below the bottom edges of the flanges to remove the blank from the first mentioned member. 15
30. A machine for making paper containers such as cups including means for supporting a stack of blanks, a member for removing the uppermost blank from the stack, said member having depending flanges, means for applying 20 adhesive to the bottom edges of the flanges, a second member normally positioned on a plane above the bottom edges of the flanges, and means for moving the members in unison to engage the adhesive on the flanges with the uppermost blank of the stack to remove the same and to move the second member relative to the first member to a position on a plane below the bottom edges of the flanges to remove the blank from the first mentioned member. 25
31. A machine for making paper containers such as cups including means for supporting a stack of blanks, a folding unit, a transfer member for receiving blanks from the stack and to position the same over the folding unit, said 30 transfer member having an opening therein, and means operable through the opening of the transfer member for forcing the blank into and through the folding unit. 35
32. A machine for making paper containers such as cups including means for supporting a supply of blanks, a folding unit, a member for transferring individual blanks from the supply to the folding unit, oppositely disposed gauge members positioned on and carried by the transfer member to receive a blank therebetween, gauge members carried by the folding unit and adapted to engage an edge of the blank, and means for moving the blank from the transfer member to the folding unit. 40
33. A machine for making paper containers such as cups including means for supporting a supply of blanks, a folding unit, a member for transferring individual blanks from the supply to the folding unit, oppositely disposed readily adjustable gauge members positioned on and carried by the transfer member to receive a blank therebetween, readily adjustable gauge members carried by the folding unit and adapted to engage an edge of the blank, and means for moving the blank from the transfer member to the folding unit. 45
34. A machine for making paper containers such as cups from blanks including a folding unit, and a forming member adapted for forcing a blank into and through the folding unit, said folding unit including members cooperating with the forming member to fold the blank to provide upwardly extending opposite face portions and to overlap the side edges thereof, and the forming member including means for creating a suction 50
- to initially draw the opposite face portions of the blank into engagement with the forming member and then to draw the edges of the blank into overlapped relation. 5
35. A machine for making paper containers such as cups including a folding unit, means for positioning blanks relative to the folding unit, a rotatable member having circumferentially spaced pockets, means for forcing the blanks into and through the folding unit to shape the same 10 into containers having overlapped edge portions, the overlapped edge portions being connected by an adhesive and the containers being successively received in the pockets of the rotatable member, and means controlled by the rotation of the 15 rotatable member for creating suction in the spaced pockets during a portion of the rotation of the member for tightly drawing the containers therein. 15
36. A machine for making paper containers such as cups including means for folding blanks into containers and securing overlapped edge portions thereof, a rotatable member having circumferentially spaced pockets to successively receive the shaped containers, and means controlled by rotation of the rotatable member for creating a suction in the spaced pockets for drawing the containers therein. 20
37. A machine for making paper containers such as cups from blanks including a folding unit, 25 a pocket positioned beneath the folding unit, and a forming member engageable with the blank on its transverse medial line and adapted for forcing the same into and through the folding unit and into the pocket by a single continuous movement, the forming member entering the pocket for deposit of the formed container therein. 30
38. A machine for making paper containers such as cups from blanks, including a folding 35 unit, a pocket positioned beneath the folding unit, and a forming member engageable with the blank on its transverse medial line and adapted for forcing the same into and through the folding unit and into the pocket, said folding unit including slideable members cooperating with the forming member to fold the blank upwardly into engagement with the forming member, and members engageable with the edges of the blank for overlapping the same to complete the container. 40
39. A machine for making paper containers such as cups from blanks, including a folding unit, a pocket positioned beneath the folding unit, and a forming member engageable with the blank on its transverse medial line and adapted for forcing the same into and through the folding unit and into the pocket, said folding unit including slideable members cooperating with the forming member to fold the blank upwardly into engagement with the forming member, and pivotally mounted 45 members engageable with the edges of the blank for overlapping the same to complete the container. 50
40. A member for making paper containers such as cups from blanks including a folding unit, a pocket positioned beneath the folding unit, and a forming member engageable with the blank on its transverse medial line and adapted for forcing the same into and through the folding unit and into the pocket by a single continuous movement, said folding unit including members for successively engaging the blank for folding the same upwardly into engagement with the forming member and for folding the edges into overlapped 55 relation to complete the container and the form- 60

ing member entering the pocket for deposit of the formed container therein.

41. A member for making paper containers such as cups from blanks including a folding unit, a pocket positioned beneath the folding unit, and a forming member engageable with the blank on its transverse medial line and adapted for forcing the same into and through the folding unit and into the pocket by a single continuous movement,

said folding unit including vertically spaced members for successively engaging the blank for folding the same upwardly into engagement with the forming member and for folding the edges into overlapped relation to complete the container and the forming member entering the pocket for deposit of the formed container therein.

HERMAN CAREW.
